WINDOW LATCH

John W. Wexler, Silver Spring, Md.

Application April 8, 1953, Serial No. 347,459

3 Claims. (Cl. 292—153)

This invention relates to window latch devices, and more particularly, to window latches of the sliding type.

A main object of the invention is to provide a novel and improved window latch device which is simple in construction, is easy to install, and which provides reliable securing of a window in either a fully closed or in a partly closed position.

A further object of the invention is to provide an improved window latch device which is inexpensive to manufacture, which is sturdy in construction and which is neat in appearance.

A still further object of the invention is to provide an improved window latch which may be employed to secure a window in either a fully closed or partly closed position, said latch being arranged so that it cannot be shaken loose by vibrating or shaking the window from the outside, and can only be unfastened from inside the window.

Further objects and advantages of the invention will become apparent from the following description and claims, and from the accompanying drawings, wherein:

Figure 1 is a front elevational view of a fragmentary portion of a window structure provided with a window sash locking device constructed in accordance with the present invention.

Figure 2 is a vertical cross-sectional view taken on line 2—2 of Figure 1.

Figure 3 is a horizontal cross-sectional view taken on line 3—3 of Figure 1.

Figure 4 is a side elevational view of the window sash locking device shown in Figures 1 to 3.

Figure 5 is a vertical transverse cross-sectional view taken through the slide member of a modified form of window sash locking device according to the present invention.

Figure 6 is a view similar to Figure 5, but showing another modification of the present invention.

Figure 7 is a fragmentary view similar to Figure 6, of the upper portion of the main detent element of a window sash locking device according to the present invention, showing another modified form thereof.

The present invention is an improvement on the window latch disclosed in United States Patent No. 2,505,598 to John W. Wexler, issued April 25, 1950.

Referring to the drawings, 11 designates a conventional window sash having a top sash member 12 and a bottom sash member 13. The sash members 12 and 13 are slidably received in conventional vertical guide ways in the side members of the window frame.

Secured to the top meeting rail 15 of lower sash member 13 adjacent the side margin of the sash member, as by screws 16, 16, is a base member 17 which is generally rectangular in shape and which is formed with the inturned side flanges 20, 20, defining lateral guide ways. Slidably mounted on base member 17 is the latch member 21, said latch member having a rectangular main body 22 whose side edges are received under the inturned flanges

2

20, 20, whereby the latch member is guided for longitudinal movement on the base member 17.

At one end of the body 22 is the vertically projecting detent member 25 having smoothly rounded, upwardly tapering side edges 26, 26. The detent member 25 may be formed at its top end with a horizontal seat portion 27, or, alternatively, with an arcuate notch 27', as shown in Figures 5, 6 and 7.

The bottom corners 28, 28 of the detent member 25 extend laterally beyond the side edges of the horizontal main body 22 of the latch member, as is clearly shown in Figures 3, 5 and 6, whereby said corners abut the ends of the inturned flanges 20, 20 when the latch member is retracted from sash 12, to prevent the latch member from becoming detached from base member 17 in normal use. The intermediate portion of detent member 25, in the form of the invention shown in Figures 1 to 4, is formed with a substantially circular opening 29 having vertical opposed slot portions 30, 30 connecting therewith.

At the other end of the body 22 is a vertical lug 31 of a width small enough to be received between the opposed edges of the guide flanges 20, 20 when the latch member is assembled with the base member 17. Lug 31 functions as a manual grip or handle for the latch member.

Designated at 40 is a further latch element which is pivotally connected at 41 to a side marginal portion of the main detent member 25. The latch element 40 is formed with a slot 42 opening at its bottom edge and being substantially registrable with the circular aperture 29, as well as with the vertical slot portions 30, 30. The latch element 40 is formed at the end of its bottom edge with the outwardly projecting finger tab 43 which serves both as a means for manually rotating the latch element and as an additional weighting means for biasing the latch element 40 downwardly.

Vertically aligned with the aperture 29 and screwed into the side stile 32 of upper sash 12 are a plurality of headed screws 33, the lowermost screw being positioned just above the level of seat 27 of the detent member 25 when the upper sash 12 is in its fully raised position with respect to lower sash 13. The heads of screws 33 project outwardly from the stile 32 a distance slightly greater than the combined thickness of detent members 25 and 40, so that the head of a screw may overlap the outer surface of detent element 40 when the screw is received through aperture 29 and slot 42, as shown in dotted view in Figure 2.

To lock the window in fully closed position, latch member 21 is pushed inwardly so that detent member 25 abuts the stile 32 and seat 27 underlies the lowermost screw 33. Upper sash 12 may then be slightly lowered so that the head of said lowermost screw overlaps the outer surface of detent member 25 and the screw shank engages the seat 27. To lock the window in a partly opened position, the detent member 25 is engaged with one of the screws 33 with the screw shank projecting through the aperture 29, the detent element 40 being then manually rotated to engage the slot 42 over the screw shank. The sash may then be slightly adjusted so that the screw shank is engaged in one of the vertical slot portions 30. If an attempt is made from the outside to further open the window by moving the sash up or down or by shaking the sash, the screw shank engages in one or the other of the slot portions 30 and the weighted detent element 40 prevents the detent member 25 from being shaken away from the screw head. Thus disengagement of the detent member 25 from the screw by shaking the window sash from the outside is effectively prevented. To disengage the detent member, the screw head must be centered in the circular opening 29 and the detent element 40 must be manually lifted

off the screw. This can only be done from inside the window.

In the embodiment illustrated in Figure 5, the vertical slot portions 30 are omitted and only a circular aperture 29 is employed in the detent member, shown at 25.

In the embodiment illustrated in Figure 6, a single vertical slot portion 30 is employed connecting with the circular aperture 29. This slot portion 30 may be below the aperture 29, as illustrated in Figure 6. Alternatively, the single vertical slot portion may be above the circular aperture 29, as illustrated in Figure 7.

It will be readily apparent that in any of the forms of the invention above described, the weighted pivoted detent element 40 engages the shank of the screw 33 at its slot 42 and serves as a safety catch to prevent the main detent member 25 from being disengaged from the screw when the window sash is shaken or moved up and down from the outside. The slot 42 is just wide enough to receive the screw shank, with sufficient play to allow the sash to be adjusted slightly so that the shank may engage in one of the vertical slot portions 30, in the case of the forms of the invention illustrated in Figures 1 to 4, 6 and 7.

While certain specific embodiments of an improved window latch device have been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In a window latch device, a latch member comprising a base portion having a main detent element projecting upwardly from an end thereof, said main detent element being formed with an opening including a vertical slot portion of lesser width than the maximum width of the opening, a further detent element freely pivoted to said main detent element at its inside surface at a point spaced horizontally from said opening and having a notch in its bottom edge registerable with said opening and arranged in opposition to said vertical slot por-

tion, and a locking seat on the top edge of said main detent element above said opening.

2. In a window latch device, a latch member comprising a base portion having a main detent element projecting upwardly from an end thereof, said main detent element being formed with an opening including opposed vertical slot portions of lesser width than the maximum width of the opening, a further detent element freely pivoted to said main detent element at its inside surface at a point spaced horizontally from said opening and having a notch in its bottom edge registerable with said opening and arranged in opposition to one of said vertical slot portions, and a locking seat on the top edge of said main detent element above said opening.

3. In a window latch device, a latch member comprising a base portion having a main detent element projecting upwardly from an end thereof, said main detent element being formed with an opening including opposed vertical slot portions of lesser width than the maximum width of the opening, and a further detent element freely pivoted to said main detent element at its inside surface at a point spaced horizontally from said opening and having a notch in its bottom edge registerable with said opening and arranged in opposition to one of said vertical slot portions, said main detent element being formed with a notch on its top edge above said opening, defining a locking seat.
